UNITED STATES PATENT OFFICE

2,425,846

HINGED LIGHT

John Charles Frederick Trewren, Sidcup, England, assignor to J. Stone & Company, Deptford, England, a British company

Application May 16, 1944, Serial No. 535,865
In Great Britain May 21, 1943

3 Claims. (Cl. 114—178)

1

This invention of improvements in hinged lights such as are used for ships' port-holes, has for its object to provide a simple but effective tightening means for securing the glass door tightly against its seating in the closed position and, in combination therewith, means for enabling the glass door to be held in different angular positions when opened so that the amount of ventilation through the door opening is readily controlled.

According to this invention, a revolvable wedging ring, revolvably mounted on the hingedly mounted glass door, is provided with a locking device such as a pin projection or tooth, which, by turning the ring, when the glass door is in an open position, can be brought into engagement with a selected one of several indentations or teeth on a fixed hinge lug, such engagement being effective for retaining the glass door in a corresponding angular position. Various degrees of opening between minimum opening and full opening can be provided for.

In order to enable the invention to be readily understood, reference is made to the accompanying drawing, wherein—

Figure 1 is an elevation, as seen from the interior of a ship, of a closed port-hole light embodying the present improvements.

Figure 2 is a plan section taken on the line II—II of Figure 1.

Figure 3 is a plan section taken on the line III—III of Figure 1, and

Figure 4 is a section similar to Figure 3 but showing the hinged door or light fastened in an open position.

Referring to the drawing the hinged door or light comprises a circular gun metal ring *a* having lugs *a*¹ and formed with an annular and internally screw threaded flange *b* within which is inserted the glass *c* and a screw threaded glazing ring *d* for securing the glass. In one face, the door ring is formed with a circular groove in which is fixed a packing ring *e* for making watertight engagement with a seating lip *f* on the fixed frame *g*. In its periphery, the door ring is formed with a rectangular groove one side of which is open towards the other face of the ring. In this groove there is revolvably inserted a wedging ring *h*, which is retained in the groove by a housing ring *j* secured by screws *k* (Figure 2) to the said other face of the door ring. Around its periphery, the wedging ring *h* is formed with two or more lugs *h*¹ with inclined faces to serve as wedges. It is also formed or fitted at another point on its periphery, and distant from the hinge

5 lugs *a*¹, with a handle *l* (Figure 1). For a small light, only two wedge lugs *h*¹ may be required and these would be disposed so as to be spaced by a considerable angle from the hinge lugs *a*¹ as shown in Figure 1. At a point on its periphery adjacent to one of the hinge lugs, the wedging ring *h* is formed or fitted with a projection *h*² which may have a form somewhat like that of a pinion tooth. The circular fixed frame *g* is formed at appropriate points with claw-like lugs *m* having wedging surfaces for co-operating with those of the wedge lugs *h*¹ of the wedging ring *h*. Also, it is formed with two fixed hinge lugs *m*¹*m*² with which the hinge lugs *a*¹ of the door are 10 hingedly engaged. One of these fixed lugs, namely the lower one marked *m*², is formed around its periphery with a number of teeth or indentations so that this lug has somewhat the appearance of a segment of a fixed pinion as 15 seen clearly in Figures 3 and 4. When the door is closed, as in Figures 1 to 3, the wedging ring *h* is turned clockwise by means of its handle *l* through a small arc. This turning movement may be limited by a stop pin *n* (Figure 1) on the 20 door ring engaging in an arcual slot *o* in the wedging ring, and is effective for causing the wedge lugs *h*¹ to engage the wedge surfaces of the claws *m* and effect a tight seating of the door *a*. When the door is to be opened, the wedging 25 ring *h* is turned reversely and this removes the wedge lugs *h*¹ from behind the claws *m* so that the lugs *h*¹ clear the claws *m* as the door is turned upon its hinges. When the door has been opened 30 to a desired extent, the wedging ring is turned 35 in the same direction as that for producing the wedging action but this movement now causes the tooth-like projection *h*² to enter between two of the teeth formed on the fixed hinge lug *m*² so that the door *a* is now locked in the desired open 40 position. This will be understood from Figure 4 which shows the door *a* swung to a position at right angles to the fixed frame *g* and locked in that position by engagement of the projection *h*² in the notch between the second and third teeth of the fixed hinge lug *m*². If the hinges are 45 disposed at the side of the door, the position of the handle *l*, when the door is locked in an open position, is a little lower than the position seen in Figure 1 and is such that its weight tends to 50 keep the ring *h* in locking engagement and to resist vibrational effects which otherwise might possibly cause the ring to turn in the direction for unlocking the projection *h*² from the teeth of the lug *m*².

55 The advantages of the device are its simplicity,

the quickness and ease with which the door can be closed and tightened on its seating, the absence of gears or screw fastenings, and the utilization of a single part, namely the wedging ring *h*, for the dual purpose of tightly sealing the door in a closed position and for locking it in a selected open position.

If desired, a dead light can be fitted and can either be hinged separately or on the same hinge pin as the door *a*. This dead light may also be fitted with a wedging ring of the kind described.

I claim:

1. A hinged port light comprising, a fixed circular frame, a swingable circular frame, hinge means connecting the two frames so as to permit swinging of the swingable frame relative to the fixed frame, a wedging ring revolubly mounted on said swingable frame for circular adjustment around the latter, wedge lugs on said wedging ring, claw lugs on said fixed frame for cooperating with said wedge lugs when said wedging ring is circularly adjusted in one direction, a series of stop formations spaced around the hinge axis in a plane perpendicular to such axis, and means on said wedging ring to be brought into interlocking engagement with a selected one of said stop formations by a circular adjustment of said wedging ring after said swingable frame has been swung to an open position in which it is angularly disposed in relation to the fixed frame.

2. A hinged port light comprising a fixed circular frame, a swingable circular frame, hinge means comprising hinge lugs and a hinge pin connecting the two frames so as to permit swinging of the swingable frame about the axis of the hinge pin, a wedging ring revolubly mounted on

said swingable frame for circular adjustment around the latter, wedge lugs on said wedging ring, claw lugs on said fixed frame for cooperating with said wedge lugs when said wedging ring is circularly adjusted in one direction, a series of indentations in alternation with projections formed on one of the hinge lugs, and a projection on the wedging ring adapted for being brought into interlocking engagement with a selected one of said indentations by a circular adjustment of said wedging ring in an appropriate direction after said swingable frame has been swung to an open position in which it is angularly disposed in relation to the fixed frame.

3. A hinged port light as claimed in claim 2, and further comprising an operating handle on the wedging ring, the said handle being so disposed that its weight tends to turn the wedging ring in the direction for preserving interlocking engagement between the projection on the wedging ring and a selected one of the said indentations.

Certificate of Correction

Patent No. 2,425,846.

August 19, 1947

JOHN CHARLES FREDERICK TREWREN

It is hereby certified that the name of the assignee in the above numbered patent was erroneously described and specified as "J. Stone & Company" whereas said name should have been described and specified as *J. Stone & Company Limited*, as shown by the record of assignments in this Office; and that the said Letters Patent should be read with this correction therein that the same may conform to the record of the case in the Patent Office.

Signed and sealed this 25th day of November, A. D. 1947.
